UNITED STATES PATENT OFFICE.

CASIMIR J. WOOD, OF SAN FRANCISCO, CALIFORNIA.

TENON.

1,369,154.

Specification of Letters Patent. Patented Feb. 22, 1921.

Application filed May 12, 1919. Serial No. 296,673.

To all whom it may concern:

Be it known that I, CASIMIR J. Wood, a citizen of the United States, residing at San Francisco, in the county of San Francisco and State of California, have invented certain new and useful Improvements in Tenons, of which the following is a specification.

My invention is a tenon particularly useful in wooden pipe joints.

My invention is illustrated in the accompanying drawing which forms a part of this specification and the appended claims.

Referring to the drawing:

15 Figure 1 is a side elevation of a wooden pipe section with a tenon on the end thereof embodying my invention.

Fig. 2 is a longitudinal section of said pipe section.

20 Fig. 3 is a longitudinal section of a pipe joint embodying my invention.

Fig. 4 is a fragmentary cross section of the pipe embodying my invention.

In the drawing 1 indicates a section of a 25 wooden pipe on the end of which is formed an annular tenon 2. The pipe section is formed by a plurality of interengaging tongue-and-grooved boards 3. A wire 4 is wrapped around the pipe up to the tenon 2, compressing the boards tightly together at their joints up to the tenon, the boards flaring outwardly in the tenon to the end thereof. The outer surface of the tenon is cut conical shape, diverging to the end of 35 the tenon parallel to the inner surface thereof. A shoulder 5 is formed between the tenon 2 and the outer surface of the pipe section.

When the tenons on the ends of two pipe 40 sections are introduced into a joint sleeve 6, they are compressed straight, the boards 3 in the tenons being compressed tightly together at their joints, so that the outer surface of the tenons fit the inner surface of the sleeve tightly, and the inner surface of the 45 tenons extends parallel to the inner surface of the pipe, as shown in Fig. 3, and not in-

wardly beyond the inner surface of the pipe in the path of the water flowing through the pipe.

50

A pipe joint including my tenon is most effective against leakage.

Having described my invention, I claim:

1. In a pipe section of compressible material, a tenon on the end of said section of 55 conical formation diverging outwardly toward its outer end.

2. A pipe section composed of a plurality of longitudinally disposed strips arranged side by side and bound together by external 60 means, a tenon integral on the end of said pipe section and free of said binding means, said tenon being of a less diameter than the pipe section and of conical formation diverging outwardly toward the end thereof. 65

3. A pipe composed of a plurality of longitudinally disposed strips arranged side by side and bound together by external means, a tenon on one end of said pipe sections formed by the projecting ends of said strips, being 70 free of said binding means, the ends of the strip forming the tenon being slightly separated at their contiguous edges and increasing toward their outer ends, whereby the tenon takes a conical formation diverging outwardly toward its outer end. 75

4. A pipe joint comprising in combination, a pair of pipe sections formed of longitudinally disposed strips arranged side by side and secured together by external means, 80 a tenon on adjacent ends of the pipe sections formed by the projecting ends of said strips and free of said binding means, said ends of the strips forming the tenons being slightly separated at their contiguous edges 85 and adjacent its outer end, whereby the tenons assume a slightly conical formation diverging outwardly toward their ends, and a sleeve in which said adjacent tenons are inserted and which brings the separated 90 edges of the tenon together, thereby forming a tight joint.

In testimony whereof I affix my signature.
CASIMIR J. WOOD.
